(57) **CLAIM**

The ornamental design for a cabinet, as shown and described.

DESCRIPTION

FIG. 1 is a top perspective view of a cabinet, showing my new design in a first position of use with the doors of the article closed;

FIG. 2 is second top perspective view thereof, shown in a second position of use with the doors of the article open;
 FIG. 3 is a front view of the cabinet, shown in the first position of use;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the cabinet, which form no part of the claimed design.
